UNITED STATES PATENT OFFICE.

CHARLES HUGH SOOY, OF NORTH SAN JUAN, CALIFORNIA.

SPRING-PROTECTOR FOR CARRIAGE-TOP BOWS.

SPECIFICATION forming part of Letters Patent No. 775,583, dated November 22, 1904.

Application filed April 9, 1903. Serial No. 151,794. (No model.)

To all whom it may concern:

Be it known that I, CHARLES HUGH SOOY, a citizen of the United States, residing at North San Juan, in the county of Nevada and State 5 of California, have invented certain new and useful Improvements in Spring-Protectors for Bows of Carriage-Tops, of which the following is a specification.

My invention relates to an improved protector for the bows of tops for buggies or carriages, and is especially applicable for tops the frames of which swing on pivots at the sides and have side bars, known as "bows," which are supported by rails when the frame 15 is lowered. It has been found that the continued vibration of the carriage-frame transmitted through the said bows to the carriage-top has the effect of eventually bending and even breaking said bows. This is particularly the case when the carriage is used over 20 rough roads.

It is the object of my invention to provide a cheap and simple means for avoiding this loss and annoyance. I obtain these ends by 25 the novel combination of parts hereinafter fully specified, and particularly pointed out in the claim.

In the accompanying drawings, Figure 1 is a side elevation of a portion of a buggy and 30 buggy-top equipped with my improvement, showing the bow of the buggy-top resting upon its support. Fig. 2 is an enlarged side view of said bow resting on the rail, and Fig. 3 is a perspective view of the spring and 35 clamping device detached.

Referring to the drawings, 1 represents the frame of the buggy, and 2 the buggy-top, having the bow 3 at each side, which resting upon the rail 4 supports the weight of the whole 40 top when lowered. In my invention I interpose between said bow and rail a bow-spring 5, which is made of a strip of spring metal, secured at one end, as shown at 6, to the bow 3, the other end being free to slide along said 45 bow. As will be seen from the drawings, the

spring is curved away from the bow a considerable distance in the center, so that considerable amplitude of resilient movement is permitted to said spring. Thus the whole vibration which ordinarily is imparted to the carriage-top is now taken up by the spring. The fixed end of the spring can be secured in any desired manner to the bow, and in the present instance I have shown it secured by providing at the end of the spring two ears 7, through 50 which pass the threaded ends 8 of a U-clamp 9, which is passed around the bow, said threaded ends being secured by nuts 10 on the under side of said ears. The spring is extended beyond said clamping device and is curved to 55 fit snugly around the bow, as shown at 12, as is likewise the free end 11 of the spring, which slides along the under side of the bow.

It will be understood that I do not limit myself to the precise construction of spring 60 here shown, still less to the precise manner of attaching the fixed end of the spring to the bow; but

What I claim is—

In combination with the bow of a carriage-top frame, and the support therefor upon the carriage-frame, a bow-spring plate interposed therebetween having lateral ears, a U-clamp around the bow having threaded ends passed through said ears, nuts on said threaded ends 70 on the lower side of said ears, the other end of the bow-spring being concave and fitting against the under side of the bow and sliding freely thereunder, and the first end having an extension beyond the ears pressing against 75 the under side of the bow, substantially as described.

In witness whereof I have hereunto set my hand in the presence of two subscribing witnesses.

CHARLES HUGH SOOY.
